INVENTOR.

UNITED STATES PATENT OFFICE.

ROBERT GAIR, OF NEW YORK, N. Y.

DESIGN FOR A PAPER-LACE MAT.

40,322.

Specification for Design.

Patented Oct. 26, 1909.

Application filed August 5, 1909. Serial No. 511,474. Term of patent 3½ years.

To all whom it may concern:

Be it known that I, ROBERT GAIR, a citizen of the United States, residing at New York, borough of Brooklyn, in the county of Kings, State of New York, have invented a new, original, and ornamental Design for Paper-Lace Mats, of which the following is a full, clear, and exact specification.

In the accompanying drawing, the figure

is a plan view of a paper lace mat showing my design.

I claim.

The ornamental design for a paper lace mat as shown.

ROBERT GAIR.
